UNITED STATES PATENT OFFICE.

FRANK HERRICK, OF RHINEBECK, NEW YORK.

EGG-TESTER.

SPECIFICATION forming part of Letters Patent No. 423,685, dated March 18, 1890.

Application filed July 23, 1889. Serial No. 318,369. (No model.)

To all whom it may concern:

Be it known that I, FRANK HERRICK, of Rhinebeck, in the county of Dutchess and State of New York, have invented a new and useful Improvement in Egg-Testers, of which the following is a full, clear, and exact description.

My invention relates to an improvement in egg-testers, and has for its object to provide a device capable of expediting the work of "candling" eggs and to provide a means whereby the eggs may be tested accurately and conveniently in a lighted room.

The invention consists in the novel construction and combination of the several parts, as will be hereinafter fully set forth, and pointed out in the claims.

Reference is to be had to the accompanying drawings, forming a part of this specification, in which similar letters and figures of reference indicate corresponding parts in all the views.

Figure 1 is a perspective view of the device. Fig. 2 is a perspective view with the hood removed, and Fig. 3 is a central vertical section, through Fig. 1.

The body 10 of the device is preferably made in the shape of a box of greater length than width, being provided with an essentially-open top and bottom 11 and 12 and a door 13 at the front, which door is usually hinged and provided with a hook 14, capable of engaging an eye 15 upon one side of the box, as illustrated in Fig. 2; or other equivalent forms of fastening device may be employed. In the door a trefoil opening is produced, which opening is covered by a strip 16 of elastic material—such as leather, for instance—in which material three triangularly-arranged openings 17 are produced, as best shown in Fig. 2. One lower opening a and the upper opening a' are essentially oval, and the other lower opening a^2 is practically circular. At the rear of the strip 16 containing the openings a slide or damper 18 is placed, pivoted at one upper end, as shown in Fig. 2, and provided with a segmental slot 19, through which a pin 20 is passed, as is also best shown in Fig. 2, which pin limits the upward movement of the damper or slide and guides it in its downward movement. The downward movement is limited by means

of a stop 21, integral with the outer lower end of the damper, adapted to contact with one side edge of the apertured strip 16, and a handle 22, of any approved construction, is formed integral with or attached to the outer edge of the damper above the said stop. The damper is of such width that when it is carried downward to the closed position between the opposed faces of the door and the strip 16 it will cover only two of the openings 17—for instance, the openings a and a^2 .

Within the box-like body 10 a bracket 23 is secured, on which bracket any form of lamp 65 24 is adapted to be located. I desire it, however, to be distinctly understood that I do not confine myself to any particular form of bracket, and that the said bracket may be dispensed with entirely and the lamp be placed 70 upon the center of a spider 25, secured in the bottom of the box or at any point in its length.

In connection with a box constructed as described I employ a hood 26. This hood comprises a rigid top plate 27, to the front and side edges of which a piece of cloth 28 is attached, or any material which will shade the openings covered by the strip 16. The top plate 27 is provided at each side of the inner end with a bifurcated projection 29, which projections 80 are adapted to pass over an eye 30, secured to the edge of the door, and to the sides of the top plate a hook 31 is pivoted, whereby the top plate of the hood is fastened to the door. As a further support for the hood, a bail 32 is 85 pivoted to its sides, the upper portion of which bail contacts with hooks 33, secured to the door near its upper edge. Thus the hood may be very quickly applied and speedily detached when not wanted. The cloth of the 90 hood is sufficiently long to extend down to a point at or near the bottom of the box-body, where it may be secured in any approved manner, preferably by a hook, as illustrated, and in the front of the cloth opposite the apertured strip 16 of the body an opening 34 is 95 made sufficient to admit the face of the operator. The device is adapted to be hung upon the wall or other support at a convenient height for the operator to place his face at 100 the opening 34.

In operation, when in a lighted room, the hood is attached to the box, and the operator, placing his face in or near the opening 34,

grasps the eggs in the usual manner—that is, three in each hand—and placing them over the openings a , a' , and a'' is enabled while holding them to determine whether they are 5 fresh or not by the passage of the light through the shell.

If there is any doubt with reference to the 10 freshness of a single egg, for instance, of the three, that egg is placed at one side, and the 10 other two are dropped into a suitable receptacle. The damper 22 is then slid down, closing two of the openings, and the egg is placed at the single opening, whereby all the light is concentrated at that point. 15 By means of this apparatus the operator is enabled to take three eggs with each hand and pass them before the openings in the strip 16, thereby greatly expediting the operation of candling, which has heretofore been very 20 tedious and has consumed considerable time. When in a dark room, the hood need not be used.

I desire it to be understood that, if desirable, reflectors of any approved construction 25 may be used in connection with the device.

Having thus described my invention, I claim as new and desire to secure by Letters Patent—

1. In an egg-tester, the combination, with a box-like body having an opening in one side and means for supporting a lamp, of a strip 30 of pliable material covering the body-opening, provided with apertures triangularly grouped, and a damper held to slide beneath the said strip, capable of closing one or more of the apertures therein, substantially as 35 shown and described.

2. In an egg-tester, the combination, with a box-like body provided with an essentially trefoil opening in one side and means for supporting a lamp within the body, of a pliable strip covering the body-opening, provided with apertures adapted to receive eggs triangularly grouped, a damper held to slide at the back of the apertured strip, capable of closing one or more of the openings therein, and 40 a detachable hood secured to the box, having a face opening and covering that side of the box containing the testing-strip, substantially as 45 specified.

FRANK HERRICK.
